UNITED STATES PATENT OFFICE.

CARL A. MATSON, OF LYNNFIELD, MASSACHUSETTS, ASSIGNOR TO MATSON LACE TIPPING MACHINE COMPANY, OF BOSTON, MASSACHUSETTS, A CORPORATION OF MASSACHUSETTS.

PROCESS OF MAKING A NONMETALLIC LACE TIP.

Application filed April 5, 1923. Serial No. 630,134.

To all whom it may concern:

Be it known that I, CARL A. MATSON, a citizen of the United States, and resident of Lynnfield, in the county of Essex and State 5 of Massachusetts, have invented an Improvement in Process of Making a Nonmetallic Lace Tip, of which the following description, in connection with the accompanying drawings, is a specification, like letters on 10 the drawings representing like parts.

My present invention is a novel and improved tipped lace made by a novel process, and consists in the treatment of the lace end or part to be tipped, by moldable material, 15 such as is employed in the making of a so-called "fabric tip" and then treating, compressing or otherwise molding and forming the treated portion to simulate a metallic tipped lace.

20 In the art of tipping laces, particularly shoe laces, corset laces, and other lacings for use in clothing, it has heretofore been customary to apply a metal blank about the end or portion of the lace intended to be tipped, 25 or to treat the lace by impregnating or otherwise applying a suitable substance, composition or the like, which when dried, set or hardened, would stiffen the lace sufficiently to constitute a rigid or tipped portion.

30 In my development of the art of lace tipping, I have devised novel and efficient tipping machines, such for example as that shown by my prior and copending applications Ser. Nos. 379,734, filed May 8, 1920; 35 592,814, filed October 6, 1922; 610,142, filed January 2, 1923; and I have also devised novel methods, as well as material for use in lace tipping, preferably such as is shown 40 in my copending applications Ser. Nos. 474,253, filed June 1, 1921; and 610,141, filed January 2, 1923. I find that it is possible and feasible to utilize non-metallic material for lace tipping, which will result in a completed article of manufacture substantially 45 similar in appearance to certain metallic tipped laces. Furthermore, by means of my machines and processes, I can produce such a non-metallic lace tip much more economically, at great speed in production, and very 50 simply and most efficiently with a high degree of uniformity in the resulting product resembling metallic corrugated lace tipping. Furthermore, such resulting article, viz., a

non-metallic corrugated lace tip, is more 55 satisfactory in use and desirability from the wearer's standpoint. I believe that my invention and process, whereby a non-metallic lace tip, particularly a corrugated non-metallic lace tip, can thus be made to resemble 60 a metallic lace tip, and even a corrugated metallic lace tip, is a distinct novelty in this art, and I wish to claim these features broadly.

Referring to the accompanying drawings 65 illustrating my improved type of non-metallic tipped lace and showing the preferred process of making same,

Fig. 1 is a fragmentary plan view of a portion of a lace to be tipped;

Fig. 2 is a view of the lacing after the non-metallic material is applied;

Fig. 3 illustrates the completed lace;

Fig. 4 is a cross-sectional view on the line 4-4 of Fig. 3; and

Fig. 5 is a cross-sectional view on the line 5-5 of Fig. 3.

While I have herein illustrated a single end or end portion of a lace, and the tipping material applied thereto, it will be understood that I can, and preferably will, produce the present tipped lace by making same in a machine, such for example as that shown in my application Ser. No. 592,814, wherein a double length of a lace to be tipped;—i. e., 85 a length sufficient for two end tips;—is treated and molded simultaneously, this double length being severed or cut to form the two end tips of the lace. It is, however, possible and feasible to produce the present 90 tipped lace by other machines and processes or the like. Furthermore in the attached drawings I have illustrated the present invention as applied to a tubular braided lace—of usual and customary commercial 95 form—although it is feasible to produce my non-metallic tipped lace from flat braid used in manufacturing tipped lacing if desired.

As shown in Fig. 1, the lacing 1 is of suitable size and desired color, and preferably 100 of tubular form, is supplied and may be drawn from a roll, as illustrated in my said prior patents, a predetermined portion of the lacing being treated as indicated in Fig. 2, with a mass of moldable material. Preferably this moldable material is applied to the lacing in a partially liquid or mobile state, being in proper form to adhere to the

lacing, preferably to impregnate the fibers of the lacing, and to constitute a suitable mass, which when dry or "set", will retain its final form. This material, if of celluloid or of a composition, such for example as that explained in my said copending application 472,453, or an equivalent compound, which may be rendered mobile or partially liquid, either by its own composition or by 10 heat, partially melting the same, is thus applied to and permitted to adhere to the lacing portion to be tipped. Thereupon the so-treated portion is subjected to a molding operation.

15 Heretofore such molding operation on "fabric tipped laces" has been effected by means of a plain compressing die. The resulting product, however, would not resemble a metallic tipped lace. In my present invention, 20 therefore, I subjected the treated lace portion to a corrugated die, which will result in producing an equivalent corrugated structure on the treated lace end, thus simulating almost exactly and with even greater uni- 25 formity than is possible in metallic tipped work, a metallic type of lace tip. It will be appreciated that in the application of metallic blanks to lace tips, it is frequently necessary and indeed customary to form one 30 or more corrugations on the metal, or indentations or the like, which tend to grip

or clamp the metal more firmly into the lace material. Thus the public are quite familiar with the corrugated metal tipped lace, and in my present process I simulate this corrugated metal tipped lace, but by making a non-metallic tipped lace. As shown in Fig. 3, the resulting molded fabric tipped or non-metallic tipped material, produces a series of corrugations or convolutions, having alternate convexed portions 3 and concave sections 4. This extra compression given to the treated end in the formation of the corrugated tip, produces a high degree of compression and presents a finished surface 45 very closely approximating in gloss and finish, a metallic tip of similar contour.

My corrugated non-metallic tipped lace claimed herein is also the subject-matter of my design application, Ser. No. D5437, filed 50 March 12, 1923.

My invention is further described and defined in the form of claim as follows:

The process of making a non-metallic tipped lacing, having a corrugated contour, 55 which consists in applying to a predetermined portion of the lacing, moldable material in plastic form, and thereafter molding said treated portion into corrugated form.

In testimony whereof, I have signed my 60 name to this specification.

CARL A. MATSON.
